ASSEMBLED PACKAGE OF CONTAINERS

Ralph E. Dykes, 315 2nd St., Saddle Brook, N.J. 07662,
and Robert M. Mitchell, 22 Beechwood Road, South
Norwalk, Conn. 06854

Continuation of design application Ser. No. 75,490,
June 24, 1963. This application June 20, 1966, Ser.
No. 2,730

Term of patent 14 years

(Cl. D58—2)

FIG. 1

FIG. 2

FIG. 3

FIG. 1 is an elevational view of an assembled package of containers showing our new design;

FIG. 2 is a perspective view thereof;

FIG. 3 is a perspective view thereof rotated 90° from the position of FIG. 2.

In the drawing, the broken lines indicate the outline of a transparent receptacle enclosing the package.

The essential features of our design are shown in full lines and reside in the particular arrangement of four cubically packaged tetrahedral container units each having two long and two short faces, whereby two symmetrical tetrahedral voids are defined by long faces of the cubical package, and whereby the top and bottom faces of the package are characterized by a diagonal line defined by the interface of adjacent units whose long faces define the long faces of each of the tetrahedral voids, all as shown.

This application is a continuation of our application Ser. No. D.75,490, filed June 24, 1963, entitled "Package of Assembled Containers," and now abandoned.

We claim:

The ornamental design for an assembled package of containers, substantially as shown and described.
